REFRIGERATING BOX

Filed March 29, 1928

Inventor:

Wilhelm Rohrbeck

By *Luna J. Gould*
Attorney.

UNITED STATES PATENT OFFICE.

WILHELM ROHRBECK, OF BERLIN-REINICKENDORF-OST, GERMANY.

REFRIGERATING BOX.

Application filed March 29, 1928, Serial No. 265,703, and in Germany April 4, 1927.

This invention relates to a cold box or refrigerating box having a removable ice container combined with the vessel for the melted water and in a metallic conducting connection therewith. Devices of this type are well known and the present invention resides in the provision in the water vessel below the ice container of an opening above the water level leading to the cold or refrigerating chamber and enabling bottles and similar articles to be placed in said water.

The invention is illustrated in the accompanying drawing, Fig. 1 being a cross section through the cold box and Fig. 2 a section on a larger scale of the ice container.

The cold box *a* is accessible in known manner from above. Covers *d* and *e* are provided for the ice container or casing *b* and the storage chamber *c* respectively. The ice container *b* and the vessel *f* for the melted water are formed by a single box consisting of four walls and a bottom. A partition *g* made of corrugated sheet metal is arranged in the upper part of this box with a slight inclination relatively to the outer wall *h*. Close to the lateral wall the partition *g* is provided in the depressions between the corrugations with a series of holes *i* through which the melted water runs away into the vessel *f* located below. A wide opening *l* which renders the water chamber *f* accessible and allows bottles *m* and the like to be placed therein or removed therefrom is provided above the liquid level in the wall *k* of the vessel *b* nearer the cold space or storage chamber *c*. The level of the water may be adjusted by means of a vertical pipe *n* forming part of a siphon seal *d*. The ice container *b* stands on four feet *p* on the base *q* of the cold box *a*. The ice container *b* is prevented from lying flush against the zinc wall *h* of the cold box *a* by means of bulged-out portions *r* of said wall *h*. Thus as indicated by arrows in Fig. 1 the air is able to move through the holes *s* along the outer side wall and below the melted water in the cold space *c* proper where the cooled air is warmed gradually by provisions or the like on the shelves *t* and *u* of the storage chamber *c*. It then rises and passes either through air outlets (not shown) in the cover *e* into

the open air or back through the higher openings *s* in the other wall of the ice box to the ice block *b*. *v* indicates a vessel for catching overflowing melted water.

What I claim is:

1. An ice unit for refrigerators comprising a casing having a plurality of feet on the bottom thereof to maintain it in spaced relation in the refrigerator; a metal partition in said casing at approximately the mid portion thereof to divide the casing into upper and lower sections, the upper section of the casing being adapted to receive ice and having openings in the walls thereof to permit circulation of air, and the lower section being adapted to receive the water from the melting ice to form a cooling vessel for bottles and the like and the wall of the casing of the lower section having an opening therein above the water level to receive the bottles; and means for permitting the escape of the water from the lower section and at the same time to maintain the water at any desired level.

2. An ice unit for refrigerators comprising a casing adapted to be placed in the refrigerator in spaced relation from the walls thereof and having a plurality of feet on the bottom thereof to maintain it in spaced relation from the bottom of the refrigerator; a corrugated metal partition in said casing at approximately the mid portion thereof to divide the casing into upper and lower sections and having holes therein to permit the escape of water, the upper section of the casing being adapted to receive ice and having openings in the walls thereof to permit the circulation of air, and the lower section being adapted to receive the water from the upper section from the melting ice to form a cooling vessel for bottles and the like and the wall of the casing of the lower section having an opening therein above the water level to receive the bottles; and a pipe having an air seal therein extending through the bottom of the casing and into the lower section to permit the escape of the water therefrom and at the same time to maintain the water at any desired level.

In testimony whereof I have affixed my signature.

WILHELM ROHRBECK.
